UNITED STATES PATENT OFFICE.

ROBERT C. SCHEMMEL, OF UNION CITY, INDIANA, ASSIGNOR TO BACKSTAY MACHINE
AND LEATHER COMPANY, OF UNION CITY, INDIANA.

VALANCE.

1,021,487.

Specification of Letters Patent. Patented Mar. 26, 1912.

Application filed June 6, 1910. Serial No. 565,338.

To all whom it may concern:

Be it known that I, ROBERT C. SCHEMMEL, citizen of the United States, residing at Union City, in the county of Randolph and 5 State of Indiana, have invented new and useful Improvements in Valances, of which the following is a specification.

My present invention has to do with valances for carriage, buggy, automobile 10 and other vehicle tops.

The object of the invention is the provision of a valance, adapted to be quickly and easily produced at small cost and in such manner that it has when placed the superior 15 appearance of a hand-sewed valance, and also adapted to be expeditiously tacked to the bow of a top without marring or otherwise affecting the valance face or the "raising" when the latter is employed in the 20 valance.

The invention will be best understood by reference to the following description when taken in connection with the accompanying illustration of two specific embodiments 25 thereof, while its scope will be more particularly pointed out in the appended claim.

In the drawings which are hereby made a part hereof: Figure 1 is a perspective view showing a portion of a valance constructed in accordance with my invention, as properly applied to the front bow of a top. Fig. 2 is a fragmentary front elevation of the valance *per se*. Fig. 3 is a vertical section taken in the plane indicated by 30 the line 3—3 of Fig. 1, and showing the manner in which the foundation piece of the valance is tacked to the bow. Fig. 4 is a fragmentary elevation of a valance constructed in accordance with my invention 35 and embodying a raising. Fig. 5 is a section of the same taken in the plane of the line 5—5 of Fig. 4.

Referring by letter to the said drawings, and more particularly to Figs. 1-3 thereof: 40 A is the front bow of a carriage top. B is a covering, of oil-cloth, leather or other suitable material, comprised in the top, but is not made a part of my invention, and C is the foundation piece of my novel valance, 45 which foundation piece is preferably made of leather, buckram, canvas or pasteboard in suitable width, though it may be made of any other appropriate material without affecting my invention. In addition to the 50 said foundation piece C, the valance com-

prises a covering strip D, made of leather, mohair, rubber, enamel goods or any suitable material desired, and a filling piece E which may be made of leather, buckram, pasteboard, or any other suitable material desired. The covering strip D is provided at a with a bight which receives the lower edge of the foundation piece C, and is connected thereto by through and through stitches F engaging both sides of the bight a and the 60 interposed piece C. The filling piece E is arranged at the inner side of the upwardly extending portion of the covering strip D, at a point opposite the foundation piece C, and is connected to said upwardly extending portion by through and through stitches G. It will also be noted here that the filling-piece E extends beyond the upper or outer edge of the foundation piece C, and that the stitches G are located above 65 or outwardly beyond the foundation piece C, as will readily be understood by comparison of Figs. 1 and 3.

In applying the valance produced as described, the foundation piece C is tacked to 80 the face of the top bow A, as indicated by H, while the filling piece E is held away from the foundation piece C, and then the upwardly extending portion of the covering strip D is carried rearward over the bow A 85 and is connected, together with the covering B, to the bow in the conventional manner illustrated or in any other manner consonant with the purpose of my invention.

In the modified embodiment of my invention, Figs. 4 and 5, the "raising" M, preferably a comparatively narrow piece of pasteboard, is interposed and secured by adhesive between the lower portion of the filling piece E and the inner side of the upwardly 90 extending portion of the covering strip D. The said "raising" M serves, as its name implies, to give the valance a raised and ornamental appearance at a point between the two lines of stitches F and G, but the raising may be omitted without in any way 95 affecting my invention.

As will be gathered from the foregoing the covering strip D, the foundation piece C and the filling piece E may be readily assembled, and the stitches F and G may be made on a sewing machine, from which it follows that the valance may be expeditiously and cheaply produced, and this notwithstanding the fact that it is a durable 100 105 110

structure and has when applied the superior finish and general appearance of a hand-sewed valance, or otherwise stitched valance after being placed on the top. The facility 5 with which the stitches F and G may be made on a sewing machine is due to the fact that the stitches F are located entirely below the filling piece E, while the stitches G are located entirely above the foundation 10 piece C. The portion of the covering strip D between the lower edge of the filling piece E and the stitches F permits of the filling piece E and the portion of the strip D there-over being bent at right angles to the foun- 15 dation piece C, so that the stitches G can be conveniently produced on a sewing machine after the formation of the stitches F. It will also be noticed that the extension of the filling piece E upward or outward beyond 20 the foundation piece C, and also upward or outward beyond the upper or outer side of the bow A gives an additional finish to the valance and enhances the general workman-like appearance of the same. It will also 25 be gathered from the foregoing that the foundation piece C of the valance is tacked to the bow A in such manner that the face of the valance is not injured, marred or otherwise affected, and the "raising" M 30 when employed is not displaced.

The covering strip D is flexible and hence can be readily bent to a position at right-angles to the foundation piece C, and in said 35 position can be conveniently stitched on a sewing machine to the upper portion of the filling piece E and this without interference from the said foundation piece C. It will also be observed that the flexible covering strip D is adapted to be moved together with 40 the filling piece E away from the foundation piece C, while the latter is being tacked to the bow A, and then when the filling piece E is positioned for use, its inner side is op-

posed to and covers the heads of the tacks H, with the result that there is absolutely 45 no liability of the covering strip being dis-tended or pressed outward by the said heads of the tacks.

While I have shown and described certain forms of my invention, it is to be understood 50 that I am not limited to the details or the form or relative arrangement of parts dis-closed, but that modifications may be made therein without departing from the spirit thereof. 55

Having described my invention, what I claim and desire to secure by Letters-Pat-ent, is:

The herein described valance comprising 60 a foundation piece adapted to be disposed against the face of a carriage top bow and also adapted to be tacked to said bow, a covering strip of flexible material stitched to the inner portion of the foundation piece and extending outward from said point of 65 connection and resting in front of the foun-dation piece, a filling piece arranged at the inner side of the said outwardly extending portion of the covering strip and extending outward beyond the foundation piece and 70 arranged with its inner side flat against the outer side of the foundation piece and also arranged entirely outward beyond said con-nection, and stitches connecting the outer portion of the said filling piece and the cov-75 ering strip at a point outward beyond and separated from the outer edge of the foun-dation piece.

In testimony whereof I have hereunto set my hand in presence of two subscribing wit-80 nesses.

ROBERT C. SCHEMMEL.
